UNITED STATES PATENT OFFICE.

WILLIAM O. BECK, OF RIDGEFIELD, AND ALFRED U. HOEFER, OF EAST ORANGE, NEW JERSEY, ASSIGNORS, BY MESNE ASSIGNMENTS, TO WESTERN ELECTRIC COMPANY, INCORPORATED, A CORPORATION OF NEW YORK.

ATTACHMENT FOR COIN-COLLECTORS.

1,182,964.

Specification of Letters Patent. Patented May 16, 1916.

Application filed March 25, 1915. Serial No. 16,902.

To all whom it may concern:

Be it known that we, WILLIAM O. BECK and ALFRED U. HOEFER, citizens of the United States, residing at Ridgefield, in the 5 county of Bergen and State of New Jersey, and at East Orange, in the county of Essex and State of New Jersey, respectively, have invented certain new and useful Improvements in Attachments for Coin-Collectors, of 10 which the following is a full, clear, concise, and exact description.

This invention relates to coin collectors, and more particularly to coin collectors of the postpayment type in which there is provided a tilttable receptacle adapted in one 15 position to receive and temporarily retain a coin of a particular size, and in another position to deposit the coin in a hopper, the receptacle being adapted also to permit the 20 passage therethrough of coins smaller in size than those which it is designed to collect.

The object of this invention is to provide a simple form of attachment which may be readily applied to existing coin collectors for 25 deflecting into the cash box the coins which pass through the tilttable receptacle without being deposited in the usual manner.

An attachment made in accordance with this invention comprises a sheet metal plate 30 adapted to be inserted in the coin collector, and having its surface curved to more readily facilitate the depositing of the coin in the hopper. The plate is preferably provided near its center with a raised portion 35 adjacent the end of the tilttable receptacle for changing the direction of movement of the coin, a depressed portion adjacent and below the raised portion for accelerating the speed of the coin to prevent its sticking, and 40 a second raised portion at its margin extending into the mouth of the hopper for directing the coin thereinto. An angularly disposed ear, formed integrally with the plate, is adapted to receive screw-threaded 45 attaching means for securing the attachment to the wall of the box.

In the drawings illustrating this invention, Figure 1 is an outline vertical section of a coin collector as normally constructed; 50 Fig. 2 is a view similar to Fig. 1 with the attachment of this invention applied thereto; Fig. 3 is a perspective of the attachment of this invention; and Fig. 4 is a detail sec-

tion view of the walls of the tilttable receptacle.

55

In the drawings, 5 designates a deflecting plate having a raised portion 6 formed near its center, a depressed portion 7, adjacent said raised portion 6, and a second raised portion 8 adjacent said depressed portion 7. 60 An ear portion 9 formed integrally with and at right angles to the body portion of the plate 5 is provided with threaded apertures 10 which furnish a means for fastening said plate in the collector. An elongated slot 12 65 is made near the edge opposite the one which carries the ear 9 for the purpose of accommodating mechanism (not shown) upon the interior of the collector. The general conformation of the plate 5 may best be seen 70 by reference to Fig. 3.

Fig. 1 shows one of the standard forms of coin collectors having a tilttable receptacle 15 and a refund device 16 which functions to return all deposited coins of a size which 75 will pass through the receptacle 15 when it is in its normal position as shown by the full line of Fig. 1.

In applying the attachment herein described, the refund device 16 is removed and 80 the attachment placed in the position formerly occupied by said device as is illustrated in Fig. 2. In mounting the deflecting plate 5, screws are passed through openings in the side of the box and are screwed into 85 the threaded apertures 10 of the ear 9, and when tightened, rigidly secure the plate 5 in a position so that the margin of the raised portion 8 extends into the mouth of a hopper 11 which directs the coin into the cash box. 90 The ear 9 also functions as a blocking plate for the refund channel 13, when the plate 5 is secured in position.

The receptacle 15 is adapted to receive a coin of a given denomination different in 95 size from a one cent piece, and temporarily retain the same until deposited in the cash box by the depositor tilting a mechanism (not shown) designed to collect the deposited coin. A one cent piece, however, is 100 small enough to pass through the opening between the projections formed in the walls 17 of receptacle 15, as is illustrated by Fig. 4. In its downward passage a coin of this denomination will first strike the raised portion 6 of the deflecting plate 5, and then 105

slide into the depressed portion 7. The coin in moving in and out of the depressed portion will be given an acceleration which will prevent it from sticking and be of great enough force to carry it over the second raised portion 8 by virtue of which the coin will be directed into the hopper 11, thence to the cash box.

What is claimed is:

- 10 1. An attachment for coin collectors comprising a plate having a raised portion near its center, a depressed portion upon one side of such raised portion and a second raised portion at the end below said depressed portion, and means formed integrally with said plate for receiving securing means.
- 15

Copies of this patent may be obtained for five cents each, by addressing the "Commissioner of Patents, Washington, D. C."

2. An attachment for coin collectors comprising a plate having a raised portion near its center, a depressed portion upon one side of such raised portion and a second raised portion at the end below said depressed portion, and an angularly disposed ear formed integrally with said plate for securing means.

In witness whereof, we hereunto subscribe 25 our names this 23rd day of March A. D., 1915.

WILLIAM O. BECK.
ALFRED U. HOEFER.
